UNITED STATES PATENT OFFICE.

ACTAEON L. DYKE, OF AKRON, OHIO.

MACHINE FOR MOLDING MARBLES.

SPECIFICATION forming part of Letters Patent No. 451,855, dated May 5, 1891.

Application filed October 23, 1890. Serial No. 369,065. (No model.)

To all whom it may concern:

Be it known that I, ACTAEON L. DYKE, of Akron, in the county of Summit and State of Ohio, have invented certain new and useful Improvements in Machines for Molding Marbles, &c.; and I do hereby declare the following to be a full, clear, and exact description of the invention, such as will enable others skilled in the art to which it pertains to make and use the same.

My invention relates to improvements in a machine designed more especially for molding marbles; or, in a more general sense, the machine is well adapted for molding clay or other plastic material into spherical forms; and it consists in certain features of construction and in combination of parts hereinafter described, and pointed out in the claims.

In manufacturing marbles the clay may be compressed in molds to shape it spherically, but marbles made by such means are of little value, for the reason that the grain or fiber of the material is short and is not sufficiently blended, by reason of which in firing many of these marbles crack and many others that seem perfect at the end of the firing process, if dropped upon the pavement or if thrown against each other with any considerable force, will break like clay pipe-stems. To construct a tough and consequently a durable marble, the surface thereof before firing should be rubbed under pressure to elongate the particles circumferentially and to blend the fiber, and to this end I have devised the machine illustrated in the accompanying drawings.

Figure 1 is a plan. Fig. 2 is a side elevation. Fig. 3 is an end elevation in detail. Fig. 4 is an elevation in detail, showing more especially the feed-tubes and severing device. Fig. 5 is a plan corresponding with Fig. 3, and showing respectively in solid and in dotted lines different working positions of the parts. Fig. 6 is a bottom plan of feed-lever E and the co-operating mechanism. Fig. 7 is an elevation in central section in detail of the molding-wheel and pad. Fig. 8 is a plan in section of a pad-section and its supports. Figs. 3 to 8, inclusive, are enlarged views.

A represents a suitable frame, preferably of cast-iron, and having a supporting-base A'. The form of the frame might be varied indefi-

nately, but that shown is well adapted to the purpose, being strong and comparatively light, and being in the main integral, is comparatively cheap, and at the same time gives a neat and tasty appearance to the machine.

B represents a so-called "molding-wheel," comprising two sections or halves, respectively, B' and B². This wheel is usually operated in approximately a horizontal position, in which case B' would represent the upper and B² the lower section or half of the wheel. This wheel is provided with a circumferential groove B³ at the periphery, this groove being circular or curved in cross-section, and arranged as shown, so that the groove is about equally divided between the wheel-sections B' B². These wheel-sections may be mounted loosely on the same shaft b, each wheel in such case being provided with some mechanism for transmitting power thereto—such, for instance, as driving-pulleys b' b², preferably cast integral with the wheel-sections. Shaft b connects with and is supported by frame A, and is provided with an adjustable collar b³, located next below the lower wheel-section, and the opposing ends of the hub of the wheel-sections may be of such length as to support at least a portion of the weight of the upper wheel section, but there should be no crack between the wheel-sections at the periphery thereof. The two wheel-sections may be rotated in the same direction, or by crossing one of the belts they may be rotated in the opposite direction, and they may be rotated at the same or a different speed, according to circumstances, and this matter of regulating the speed of the wheels is so well understood that it is not considered necessary to say anything further on the subject.

C is a metal band or the section of a band located opposite groove B³ and some little distance outside of wheel B, member C being rigidly secured, for instance, to frame A, the function of member C being to support the different pad-sections D D, and to this end member C has a series of lateral holes adapted to receive pins d d, that support the different pad-sections D D. Pins d are pierced laterally near their outer ends and provided with cross-pins d', and the latter, by engaging the outside of member C, serve as stops to limit the inward movement of the pad-sec-

tions, caused by the action of springs d^2 , to avoid the possibility of the pad-sections engaging wheels $B' B^2$, as engagement would result in wearing the pads. Springs d^2 are mounted, respectively, on pins d next inside of members C , these pins having screw-threaded sections for receiving nuts d^3 . These nuts bear respectively against the inner ends of the springs, and by manipulating these nuts the proper tension is given to the springs. Pins d have heads d^4 (see Fig. 7) for attaching to the body of pad-sections D . The body of these pad-sections may be constructed of wood, metal, or other suitable material, and are covered usually with cloth or other fabric or material suited to the purpose and padded between the body of the pad-sections and the covering material on the side opposite groove B^3 . The padding material may be, for instance, of cotton, curled hair, soft rubber, or other soft and elastic material, which, together with the yielding pressure supplied by springs d^2 , render the pad-sections well adapted to co-operate with wheels B in molding, for instance, blocks of clay or other plastic material into spherical forms.

The feed and severing mechanism for delivering the clay or other material in suitable and uniform quantities to the machine is as follows:

E is a vibrating feed-lever pivoted at E' , so as to operate approximately in a horizontal plane.

F is an upright crank-shaft, the crank-wrist f of which is adapted to operate in slot E^2 of the feed-lever for oscillating the latter. Slot E^2 is preferably of the curved variety shown and adapted to give a quick return as compared with the forward movement of the lever. I do not wish to limit myself to the precise form of the slot shown, as this may be varied somewhat according to circumstances, and I may find it advisable to modify the form thereof after I have used the machine for a longer time. However, the form of slot shown has thus far served the purpose well.

G is an upright feed-tube, into which the bars K of clay or other material are inserted by hand, these bars having previously been prepared so that they will fit loosely inside of the tube.

H is a vertically-adjustable stop on which the bar of material may rest as it descends by gravity inside the feed-tube.

The severing device comprises in the main a broad, thin, flat blade I , usually of steel, and preferably mounted on and rigidly secured to an arm I' . The latter is pivoted at I^2 , so that the blade may vibrate in approximately a horizontal plane past the line of the feed-tube G and in position underneath and so close to the lower end of the feed-tube that the blade will sever the material by cutting rather than by breaking that portion of the material protruding below the tube. Meantime the stop H is adjusted upward or downward, as may be required, to regulate or gage

the length of the piece of material that is severed with each stroke of the knife. The severing device is provided with a catch J , pivoted at J' to the under side of member I' . This catch is provided with a spring j , the action of which tends to hold the catch in position bearing against the stop—for instance, against stop i , in which normal position of the catch shoulder J^2 of the latter opposes the end section of lever E . Hence when lever E is swung forward it engages the catch and causes the latter to swing forward in unison with the lever, whereby the material is severed by the knife, and just as this occurs the end of lever E draws away from or becomes disengaged from shoulder J^2 , whereupon the knife stops in position, leaving at least the back portion of the blade I under and engaging the lower end of the material, whereby the latter is held from descending until such times as the knife is reversed by the return-stroke of lever E . Lever E on the return-stroke first engages the side of the catch and snubs the latter back, and when the lever passes shoulder J^2 the catch, by the action of the spring, returns to its normal position against the stop, and just as this occurs the lever engages lug I^3 of member I' , by which engagement the knife mechanism is reversed, and thereby moved from under the bar of clay or other material, so that the latter may again descend by gravity and rest on stop H . Lever E is provided with a removable block E^3 , the latter having a concaved seat E^4 somewhat corresponding with and adapted to engage the piece of material severed by the knife, and the lever and block carry forward the severed block of material and deliver it between wheel B and the opposing pad-section. (See Fig. 1.) Wheel B , moving in the direction of the arrow, would tend to carry the block of material in the same direction, subject, however, to the friction of the pad, which, by restraining the engaging side of the blank, causes the latter to be rolled and tumbled along its way, resulting in the material being quickly molded into a spherical form. The speed with which the blank is carried around by the molding-wheel will depend largely on the speed of the lower wheel-section B^2 , for the reason that the blank, by its own gravity, rests on the lower wheel-section. The upper section B^2 may be run faster or slower than the lower section, or may be run in the opposite direction, and in either case the blank will be carried along through the machine, perhaps moving a little faster or a little slower than it would if both sections of the wheel moved in unison. If, however, the two wheel-sections move in opposite direction, the lower section must always run in the direction of the arrow to feed the material for the reasons aforesaid. If then the two wheel-sections move in opposite directions, or if they move in the same direction but at different rates of speed, in either case the ball of clay or other material is subjected to a constant rub-

bing action of the wheel-sections, such rubbing tending to elongate and blend the fiber at the periphery of the ball, so that marbles made by such means are tough and strong 5 and not liable to break in firing or in subsequent use. The groove in the molding-wheel is not intended to fit the marble or other work, but only serves to guide the blank, for it is a well-known fact that spherical forms 10 may be readily produced by rolling the material between two approximately flat surfaces—for instance, by rolling the material between the palms of the hands.

The size of the marble or other work is 15 regulated primarily by the quantity of material fed into the machine at each stroke of the cutting and feeding device, and the latter is adjusted accordingly as aforesaid, so that different-sized marbles or balls may be 20 manufactured in the same groove of the molding-wheel. The bar of material K should correspond somewhat in diameter to the size of the finished work, for if the bar of material were of large size the pieces of the material cut therefrom for making small balls or marbles might be so short that stop H would be in the way of arm E. Tube G, therefore, should be removable, so that other tubes might be inserted having different bores cor- 25 responding somewhat with the sizes of the bars of material to be used. However, if tube G were large enough to accommodate the largest bar of material required, smaller tubes or bushings could be inserted therein to ac- 30 commodate bars of smaller size, in which case tube G could be permanently attached to the machine, and either arrangement would an- 35 swer the purpose. At the rear end of the pad is provided an inclined tube L, through which 40 the finished work is discharged from the machine by gravity, the centrifugal force of the machine being sufficient to cast off the ball into trough L as soon as the balls are free from the pad. The pad-sections may be, and 45 preferably are, quite short and the balls of clay or other material may follow each other in quick succession, and the crank-shaft F is speeded accordingly.

The proper speed with which the machine 50 can be operated successfully will depend somewhat upon the kind and quality of the material used, as will also the relative speed of the wheel-sections B' B², and whether these sections be run in the same or opposite di- 55 rections, and many of these details can only be determined by practice.

From the foregoing it might be inferred 60 that all the different sizes of marbles could be wrought in the same groove B³, but such is not the case. If there is to be radical change in the size of the ball or marble, a different wheel B must be inserted, having a different groove B³ to correspond somewhat with the work. Hence if the machine is in-

tended for general work several wheels B 65 should be provided for the machine, these wheels having, respectively, grooves B³ of different sizes.

What I claim is—

1. In a machine for molding plastic mate- 70 rial into approximately spherical form, the combination, with a rotating so-called "molding-wheel" constructed in sections and having a peripheral circumferential groove, of an op- posing pad located in position to engage the 75 material being wrought in the groove of the wheel, substantially as set forth.

2. In a machine for molding plastic mate- 80 rial into spherical forms, a rotating so-called "molding-wheel" having a circumferential groove at the periphery thereof, combined with an opposing pad adapted to engage the material being wrought in the groove of the wheel, such pad being backed by one or more springs, whereby the pad is applied to the 85 material with a yielding pressure, substan- tially as set forth.

3. In a machine for manufacturing marbles or other spherical articles from plastic mate- 90 rial, the combination, with a so-called "mold- ing-wheel" having a circumferential groove at the periphery thereof, of an opposing pad located opposite such groove, such pad consist- ing of a series of sections, each section being backed by one or more springs, substantially 95 as and for the purpose set forth.

4. In a machine for molding plastic mate- 100 rial into spherical form, a so-called "molding- wheel" constructed in sections or halves, the division-line being on a plane perpendicular 100 to the axis of such wheel, the wheel having a circumferential groove at the periphery there- of and located at the union of the wheel-sec- tions, in combination with a pad located op- 105 posite such groove, substantially as set forth.

5. The combination, with molding-wheel and opposing pad arranged in sections, sub- 110 stantially as indicated, of feed-tube construct- ed substantially as shown, and severing mech- anism adapted to divide the material into pieces of uniform size and to deliver the pieces successively to the machine, substan- tially as set forth.

6. The combination, with molding-wheel and opposing pad-sections, substantially as 115 shown, of feed-tube, and a vibrating knife or cutter for severing the material, a vibrating le- 120 ver adapted to actuate such knife and adapted to deliver the severed pieces of material to the machine in position between the molding- wheel and pads, substantially as set forth.

In testimony whereof I sign this specifica- 120 tion, in the presence of two witnesses, this 4th day of October, 1890.

ACTAEON L. DYKE.
